DESIGN FOR A COMBINATION CHAIR AND COT

William A. Moeller, Los Angeles, Calif., assignor to Los Angeles Spring Bed Company, Los Angeles, Calif., a corporation of Ohio

Application March 30, 1940, Serial No. 91,351

Term of patent 7 years

To all whom it may concern:

Be it known that I, William A. Moeller, a citizen of the United States, and a resident of the city of Los Angeles, in the county of Los Angeles and State of California, have invented a new, original, and ornamental Design for a Combination Chair and Cot, of which the following is a specification, reference being had to the accompanying drawing, forming part thereof.

In the drawing:

The characteristic features of my design reside in the portions shown in solid lines.

I claim:

The ornamental design for a combination chair and cot, substantially as shown and described.

WILLIAM A. MOELLER.
